CLAIM

The ornamental design for a modular photochemotherapy chamber, as shown.

DESCRIPTION

FIG. 1 is a top plan view of the photochemotherapy chamber showing our new design;

FIG. 2 is an elevation view of the control panel side thereof;

FIG. 3 is an elevation view of the door side thereof;

FIG. 4 is an elevational view of the side opposite that of FIG. 2; and

FIG. 5 is an elevational view of the side opposite that of FIG. 3.
